(57) **CLAIM**

We claim the ornamental design for a tile spacer, as shown and described.

DESCRIPTION

FIG. 1 is a top-front perspective view of a tile spacer according to an embodiment of the invention.

FIG. 2 is a top-rear perspective view of the tile spacer of FIG. 1.

FIG. 3 is a bottom-front perspective view of the tile spacer of FIG. 1.

FIG. 4 is a front view of the tile spacer of FIG. 1.

FIG. 5 is a rear view of the tile spacer of FIG. 1.

FIG. 6 is a left view of the tile spacer of FIG. 1.

FIG. 7 is a right view of the tile spacer of FIG. 1.

FIG. 8 is a top view of the tile spacer of FIG. 1.

FIG. 9 is a bottom view of the tile spacer of FIG. 1.

FIG. 10 is a top-front perspective view of a tile spacer according to an embodiment of the invention.

FIG. 11 is a top-rear perspective view of the tile spacer of FIG. 10.

FIG. 12 is a bottom-front perspective view of the tile spacer of FIG. 10.

FIG. 13 is a front view of the tile spacer of FIG. 10.

FIG. 14 is a rear view of the tile spacer of FIG. 10.

FIG. 15 is a left view of the tile spacer of FIG. 10.

FIG. 16 is a right view of the tile spacer of FIG. 10.

FIG. 17 is a top view of the tile spacer of FIG. 10; and,

FIG. 18 is a bottom view of the tile spacer of FIG. 10.

The portions of the tile spacer shown in broken lines are included for the purpose of illustrating environment and form no part of the claimed design. The portions of the tile spacer shown in broken lines having unequal length segments illustrate the boundary of the claimed design and form no part of the claimed design.
